(57) **CLAIM**

The ornamental design for a bottle, as shown and described.

DESCRIPTION

FIG. 1 is a top, front, right perspective view of a bottle showing our new design;

FIG. 2 is a front view thereof, where the rear view is mirror image of FIG. 2;

FIG. 3 is a right side view thereof, where the left side view is a mirror image of FIG. 3; and,

FIG. 4 is a top view thereof.

The uneven-length broken lines and the even-length broken lines immediately adjacent to the shaded area define the bounds of the claimed design and form no part thereof. The even-length broken lines depicting the remainder of the bottle show features that form no part of the claimed design.
